No. 12488

UNITED STATES PATENT OFFICE.

WINTHROP L. JACOBS, OF EAST ORANGE, NEW JERSEY, ASSIGNOR TO THE HARTFORD CARPET COMPANY, OF HARTFORD CONNECTICUT.

DESIGN FOR A CARPET.

SPECIFICATION forming part of Design No. 12,488, dated September 20, 1881.

Application filed August 9, 1881. Term of patent 3½ years.

To all whom it may concern:

Be it known that I, WINTHROP L. JACOBS, of East Orange, in the county of Essex and State of New Jersey, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

Three rosettes, A B C, placed nearly in a row, are separated from another row, D E F, of rosettes by a stem, G, having leaves H and sundry geometrical ornaments. Near the row

D E F of rosettes is another row, I J L, of rosettes, which, by a stem, M, is separated from a further row, N O P, of rosettes. Near the latter is another row, Q R S, of rosettes, which, by another stem, T, is separated from a row, U V W, of rosettes. Smaller rosettes and other geometrical figures are interspersed between those mentioned.

I claim—

The design for carpets, consisting of the figures A B C D E F G H I J L M N O P Q R S T U V W, substantially as shown.

WINTHROP L. JACOBS.
